To all whom it may concern:

Be it known that we, JOHN D. HAGGARD and HENRY H. The drawing represents a perspective view of a headboard or footboard for bedsteads embodying our invention.

15 The leading feature of our design resides in the arrangement of the frame part composing the headboard or footboard, which comprises the outside frame A, of light plate metal bent to form the vertical leg parts $a a$, and the connecting top cross-bar a' , the bend being rounded, as at a^2 .

Another feature of the design is the cross-bar B, which connects the leg parts and the arched spring-plate C, the respective ends of which are rolled upwardly and inwardly and 25 fastened to the cross-bar B and leg parts. The top of the spring-plate C is secured to the under side and center of the frame cross-bar a' .

Another feature is the truss X-brace E, 30 consisting of the four branches $d d d d$, united together at the middle, and the widely-extended ends attached to the leg parts.

What we claim is—
